UNITED STATES PATENT OFFICE.

THOMAS MOORE, OF BROOKLYN, NEW YORK.

PIN-TICKET.

SPECIFICATION forming part of Letters Patent No. 243,786, dated July 5, 1881.

Application filed May 20, 1881. (No model.)

To all whom it may concern:

Be it known that I, THOMAS MOORE, of Brooklyn, county of Kings, State of New York, have invented certain new and useful 5 Improvements in Pin-Tickets, of which the following is a specification.

This invention relates to pin-tickets, or that class of tickets or tags which are adapted to be secured to fibrous material by means of pins 10 attached to their rear sides and projecting at right angles therefrom, and which are sometimes known as "size and quality tickets."

The object of the invention is to lessen the cost and facilitate the manufacture of said 15 tickets; and it consists in forming in the central part of the rear side of the ticket two parallel passages extending lengthwise of the ticket and about half-way through it, so as to leave the front part of the ticket intact. The 20 wire of which the pins are made is shaped like the letter **M** with the outside legs greatly prolonged, and these prolonged legs of the **M**-shaped staple are passed through the two parallel passages made in the back of the ticket 25 as far as it is possible to do so, and the free ends are bent up at right angles, thus forming two pins adapted to be pressed through the material to which the ticket is to be secured. The pins by this means are firmly attached to 30 the ticket; and they are further caused to retain their position by the central bend of the **M**-shaped staple lying close to the back of the ticket, between the two parallel passages.

To describe my invention more particularly, 35 I will refer to the accompanying drawings, forming part of this specification, in which—

Figure 1 is a perspective view of my improved pin-ticket complete. Fig. 2 is a view of the **M**-shaped staple. Fig. 3 is a plan view 40 of the ticket, showing the two parallel passages formed in its back. Fig. 4 is a transverse section of Fig. 1, enlarged; and Fig. 5 is a similar transverse section of a completed ticket, showing a modification in the construction.

The ticket *a* is made of thick paper, card-board, or other suitable material, and has two 45 holes or passages, *a'*, in its rear side, as shown at Fig. 1, formed therein by means of a curved piercing-tool or by means of a straight piercer,

the ticket being bent to allow the piercer to enter and leave the rear side without going entirely through it.

The retaining-pins *b b* are made from a piece of wire, which is formed into a staple somewhat like the letter **M**, as shown at Fig. 2. 55 The free ends *b b*, which form the pins, and which are pointed, are passed through the holes or passages *a'* in the ticket until the outside bends of the staple come in contact with the entrance ends of the passages *a'*, when the 60 two free ends *b b* are bent up at right angles. The central bend, *c*, lies against the back of the ticket, between the two passages *a'*, thus assisting to retain the pins firmly in position.

Fig. 4 shows the relative positions of the 65 ticket *a* and the different parts of the **M**-shaped staple when the pin-ticket is completed. The part of the staple which enters the body of the ticket *a* does not pass entirely through the ticket, leaving the front face of the ticket 70 smooth and unbroken; but for some purposes, and when the tickets are made of a material which will not bear splitting to form the two parallel passages *a'*, the holes where the staple enters and leaves the ticket will be made entirely through it, so that parts of the staple 75 will be exposed at the front face, as shown at Fig. 5.

This ticket is applied to mark goods, as ordinarily, by pressing the pins through the 80 goods and then bending them down parallel to the ticket, so that they will hold the ticket securely to the same.

This construction of pin-ticket is such that it may be made on an automatic machine. 85 The card-board or other material, being fed into the machine in a strip, is passed over a guide, which bends it longitudinally. A piercer then forms the parallel holes across the strip, and the **M**-shaped staples are formed from a 90 coil of wire and passed through the holes and then bent up at right angles, as described. The strip then passes under a knife or die, which cuts the tickets from the strip completed in any desired shape.

Having now described my invention, what I 95 claim, and desire to secure by Letters Patent, is—

1. In a pin-ticket, in combination, an **M**-shaped staple and a perforated ticket, said **M**-shaped staple being passed through the body of the ticket and bent up at right angles thereto, so that the bends and free ends of the staple are at one side thereof, substantially as hereinbefore set forth.
2. The ticket *a*, provided with parallel passages *a'*, and the **M**-shaped staple *b b c*, con-

structed and combined substantially as and to for the purpose hereinbefore set forth.

In testimony whereof I have hereunto set my hand this 18th day of May, 1881.

THOMAS MOORE.
